UNITED STATES PATENT OFFICE.

JOHN H. DOUB, OF WALNUT, KANSAS.

DISPATCH HOLDER.

Application filed October 24, 1922. Serial No. 596,695.

To all whom it may concern:

Be it known that I, JOHN H. DOUB, a citizen of the United States, residing at Walnut, in the county of Crawford and State of Kansas, have invented a new and useful Dispatch Holder, of which the following is a specification.

This invention relates to dispatch holders or the like, the primary object of the invention being to provide a dispatch holder of a novel construction to render the same exceptionally light and easily handled.

Another object of the invention is to provide means for gripping and holding the dispatch to be transferred, the means being such as to insure against tearing the dispatch which is usually printed on paper.

A still further object of the invention is to provide a wooden hoop forming a part of the dispatch holder, whereby the hoop may be securely fastened to the supporting handle.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of a dispatch holder constructed in accordance with the present invention.

Figure 2 is an elevational view disclosing one edge of the dispatch holder, a portion of the hook being broken away.

Figure 3 is a sectional view taken on line 3-3 of Figure 1.

Referring to the drawing in detail, the reference character 5 designates the handle portion of the dispatch holder, which is cut away on opposite sides thereof at a point adjacent to the inner end of the handle, providing hoop engaging surfaces.

The inner end of the handle portion 5 is bifurcated providing resilient gripping fingers 6, which curve outwardly, as clearly

shown by Figure 1 of the drawing to permit an article to be positioned therebetween and securely held.

The hoop forming a part of the holder is indicated at 7 and has arms 8 which are positioned in the cut out portions of the handle 5, where the same are secured as by means of the rivets or nails 9.

In order that the arms 8 will be further held against movement, metallic bracing members 10 are provided, which have inwardly extended portions 11 lying flush with the side edges of the handle portion, the bracing members overlying the points of engagement between the ends of the arms 8 and handle 5.

Positioned on the handle 5 and overlying the bracing members, is a sleeve 12 formed preferably of sheet metal so that when the sleeve is moved to a position as indicated by Figure 1 of the drawing, the walls of the sleeve will frictionally engage the arms 8 and handle portion 5, to prevent movement thereof.

In the use of the device, a dispatch or order is positioned between the fingers 6, where the same is securely held. A person transferring the dispatch to a moving train, holds the device so that the hoop portion thereof may be readily engaged by the arm 8 of the person on the train receiving the dispatch.

Having thus described the invention, what is claimed as new is:—

1. A dispatch holder including a handle portion, integral resilient gripping fingers formed at one end of the handle portion, a hoop member having its arms secured to the handle portion, and said fingers having their outer ends curved outwardly.

2. A dispatch holder including a handle portion, said handle portion having cut out portions and having integral gripping fingers, a hoop member having arms, said arms being positioned in the cut out portions, and means embracing portions of the arms and handle portion for securing the hoop to the handle portion.

3. A dispatch holder including a handle portion, a hoop member having arms, means

for securing the arms to the handle portion, a sleeve embracing portions of the arms and handle portion for securing the hoop member to the handle portion, gripping fingers formed with the handle portion and disposed within the hoop members.

In testimony that I claim the foregoing

as my own, I have hereto affixed my signature in the presence of two witnesses.

JOHN H. DOUB.

Witnesses:

I. E. CLARK,
